UNITED STATES PATENT OFFICE.

HENRY ERASTUS WOLCOTT, OF SYRACUSE, NEW YORK.

OIL-CAN.

SPECIFICATION forming part of Letters Patent No. 327,975, dated October 6, 1885.

Application filed August 5, 1885. Serial No. 173,649. (No model.)

To all whom it may concern:

Be it known that I, HENRY ERASTUS WOLCOTT, a citizen of the United States, residing at Syracuse, in the county of Onondaga and 5 State of New York, have invented a new and useful Improvement in Oil-Cans, of which the following is a description.

This invention is an improvement in oil-cans; and it consists in certain novel constructions and combinations of parts, as will be hereinafter first fully described, and then pointed out in the claims.

In the drawings, Figure 1 is a side view of my can with parts broken away to show the 15 pivot of the cover. Fig. 2 is a vertical section of the can. Fig. 3 is a plan view of same with the cover thrown back, and Fig. 4 is a rear elevation of the combined top and cover removed.

20 The body A forms the reservoir, and has its lower end bent inwardly and upward at a, forming a hoop within the lower end of said body. A wire, B, is inserted in the body at the point of bending the hoop, and a second 25 wire, C, is secured in the extremity of the hoop or inwardly-bent portion, as most clearly shown in Fig. 2. The wire B serves to strengthen the body at its lower end or base, and the wire C furnishes a support for the 30 bottom D. This bottom is rested on the rib or flange formed by the wire C, and may be conveniently and securely soldered in place, thus forming a strong joint in a simple manner. In oil-cans difficulty has been experienced by reason of the deposit of sediment 35 in the bottom, which in time accumulates in such quantity as to foul the oil placed in the can. With the fixed tops ordinarily used it is impossible to clean out this sediment, and in 40 addition to fouling the oil, it is objectionable, because it in a short while will eat away the bottom of the can. To overcome this objection I make the combined top and cover adjustable away from over the upper end of the 45 body. This may be accomplished by hinging one edge of said top to the body so it may be turned from over the same; but the construction as shown is preferred. In this construction the top E is provided with a lateral 50 stop-flange, e, and a tubular extension or pan-flange, e', which fits snugly within the mouth of the body, while the stop e rests upon the

same, holding the top from dropping into the body. This top may be provided with a pump, E', a drip-opening, E', and an opening 55 having a hinged flap or cover, E'. By this opening the body may be filled and the height of contents thereof may be readily ascertained without removing the top. By the described construction the top may be removed conveniently for the purpose of cleansing the can or to permit the contents of the body or reservoir 60 to be more rapidly discharged than can be accomplished by means of the pump.

At its rear upper side the top is formed 65 with a narrow crescent-shaped horizontal ledge, F', from the inner edge of which rises the fixed hood F, the forward upper edge of which rests in a plane about parallel with a diametrical line drawn through the body A, 70 and this upper edge is preferably provided with an upwardly-projecting rib, f, formed preferably by wiring, as shown.

At the opposite lower ends of the forward 75 side the hood is provided with studs f', projecting outward, as shown. These studs are preferably the extended ends of the wire forming the rib f. The cover G is formed with a flat plate of metal, g, bent into the bow-shape shown, and having its forward end rested 80 on the front edge of the top and its rear edge extended over the forward edge of the hood when such cover is in closed position. This cover is pivoted at its rear lower end to the hood. This pivoting is preferably accomplished 85 in the following manner: The front edge of the cover is provided with a strengthening-wire, H, the ends of which are formed with loops h, fitting over the studs f', and completing the pivot. At its rear edge the cover 90 is provided with an inwardly-projecting flange-plate, G', arranged in a plane approximately radial to the pivot of the cover. In the open 95 position of the cover the flange-plate rests flat on the crescent-shaped ledge F', while in the closed position of the cover such plate abuts against the rib f on the upper forward edge of the hood, forming a close joint, as will be seen.

In operation the cover may be easily raised 100 in order to draw the oil, and may be closed to cover up measures, &c., when not in use.

Having thus described my invention, what I claim as new is—

1. In an oil-can, the body having its lower end bent inwardly and upward within such body, and a wire inserted at the extremity of such inwardly-bent portion, and the bottom, 5 substantially as set forth.
2. The combination in an oil-can, with the body having its lower end bent inwardly and upwardly, of wires inserted in such body at the point of bending and at the extremity of 10 such inwardly-bent portion, and the bottom, substantially as set forth.
3. The top for-oil cans, substantially as described, consisting of the hood F, having a flat plate, F', at its rear edge, and the cover G, 15 provided at its rear edge with an inwardly-extended flange, G', all arranged and adapted to operate substantially as set forth.
4. The combination, with the hood provided with lateral studs, of the cover and a wire extended from end to end of said cover, 20 and having its opposite ends formed with loops fitted over the lugs of the hood, substantially as set forth.
5. The combination of the fixed hood, lateral studs projected therefrom, the cover, and a 25 wire extended around the forward edge of said cover and having its ends formed with loops fitting over the aforesaid studs, substantially as set forth.

HENRY ERASTUS WOLCOTT.
